United States Patent Office

Des. 193,568
Patented Sept. 11, 1962

193,568

CLOCK

Hieme C. Hammer, 6N-130, Rte. 53, near Itasca, Ill.

Filed Nov. 8, 1961, Ser. No. 67,425

Term of patent 14 years

(Cl. D42—7)

FIG. 1 is a perspective view of a clock, showing my new design;

FIG. 2 is a front elevational view thereof;

FIG. 3 is a side elevational view thereof on a reduced scale;

FIG. 4 is a top plan view thereof; and

FIG. 5 is a bottom plan view thereof.

The essential features of my design reside in the portions shown in full lines in the drawings.

I claim:

The ornamental design for a clock, substantially as shown and described.
